UNITED STATES PATENT OFFICE.

JOHANN BACKHAUSEN, OF VIENNA, AUSTRIA-HUNGARY, ASSIGNOR TO
MILLS & GIBBS, OF NEW YORK, N. Y.

DESIGN FOR A CURTAIN OR COVER.

SPECIFICATION forming part of Design No. 19,451, dated December 3, 1889.

Application filed October 3, 1889. Serial No. 329,691. Term of patent 3½ years.

To all whom it may concern:

Be it known that I, JOHANN BACKHAUSEN, a subject of the Emperor of Austria-Hungary, and a resident of Vienna, Austria-Hungary, 5 have invented and produced a new and original Design for Curtains or Covers, of which the following is a specification, reference being had to the accompanying photograph, forming a part thereof, the said photograph representing a plan view of the design.

The design consists of a border-panel A, representing a series of seemingly-connected figures *a*, approximating in contour what is known as a "palm-leaf," and a series of floral spray figures *a'*. The border-figure incloses a plain field B, upon which field at one end a rectangular panel D is drawn. Upon the field B a serpentine stem *b* appears, represented 15 as bearing flowers of the rose type and hav-

ing gracefully-drooping offshoots or branches 20 *b'*, which branches also bear flowers in bloom. An addition is made to the stem-like figures and its branches of less distinct leaf-like figures *b*², resembling, somewhat, in shape a feather. In the panel D a fan-like figure *d* 25 is formed, represented as resting upon an ogee base *d'* and a scroll-like sub-base *d*². Small thistle-like figures *d*³ also appear at each side of the base.

I claim—

A design for a curtain or cover, substantially as herein shown and described.

Vienna, Austria, September 18, 1889.
